UNITED STATES PATENT OFFICE.

JOHN A. PILCHER, OF ROANOKE, VIRGINIA.

CAR-TRUCK.

1,182,705.

Specification of Letters Patent.

Patented May 9, 1916.

Application filed March 17, 1915. Serial No. 14,935.

To all whom it may concern:

Be it known that I, JOHN A. PILCHER, a citizen of the United States, residing at Roanoke, in the county of Roanoke and 5 State of Virginia, have invented certain new and useful Improvements in Car-Trucks, of which the following is a specification.

This invention relates to car trucks, and the principal object thereof is to provide an 10 improved method of forming truck side frames of rolled sections.

Other objects are to provide an improved form of spacing members and of load-supporting members, and improved methods of 15 securing the arch members to the truck oil boxes.

With these and other objects in view the invention consists in the formation, combination and arrangement of elements as 20 will be herein described and claimed.

This application follows the same lines and is supplemental to my co-pending application, Serial #13,373 filed March 10, 1915.

25 In the drawings, Figure 1 is a side elevation of a portion of a truck embodying the present improvements. Fig. 2 is a partial plan view of the same and Fig. 3 is a transverse section of the same taken on the line 30 A—B, Fig. 1. Fig. 4 is a perspective view showing the method of securing the ends of the side frame arch members together and to the oil boxes.

Referring to these drawings, wherein like 35 parts are similarly designated, 1 represents an ordinary truck wheel mounted upon one end of an axle 2. It will be understood that a plurality of such axles with two wheels each occur, one only being shown for the 40 reason that this form of truck construction is old and well known.

At 3 is a customary oil box, which, with its contained parts forms a journal bearing for the axle 2, and this also is of standard 45 M. C. B. construction.

The load of the car body is customarily carried on a center plate which is usually a part of a bolster. The bolster is usually supported on springs and the springs on a 50 spring seat, which is in turn supported on a system of rollers. These parts are not shown in the present drawings, but reference to the co-pending application referred to above will show the form of construction just described. The truck side frame is

composed primarily of a top arch bar or compression member 9, a bottom arch bar or tension member 10, and a spacing member 11. The said top and bottom arch members have spaced, vertical relationship with 60 each other at the central portion, and at the ends they converge and are co-actingly secured together so as to complete the triangle of members for truss action in the frame.

The spacing member 11 is detached from 65 the top and bottom arch bars so as to permit these arch members to be made of standard rolled sections, and is made of U-shape when viewed in side elevational view, the legs 12 and 13 thereof forming tie members 70 between the top and bottom arch members, or between the top arch bar and the bottom of the member 11, being secured to the top arch bar by means of the rivets 14, and in the present instance to the bottom portion 75 18 of the member 11 by means of the rivets 4. The bottom portion of the spacing member 11 is then secured to the bottom arch member 10 by means of the rivets 15 and the 80 clips 5. The U-shape of this spacing member 11 provides a central opening 16 which serves to admit the springs and roller seat as well as the ends of the bolster, and the 85 sides of the tie members 12 and 13 form wearing faces 17 for co-operation with the adjacent sides of the bolster. The bottom portion 18 of the spacing member 11 is adapted at 90 6 to form roller seats, thus serving as a load-receiving means for the load from these rollers, which load is transmitted 95 in turn through the bottom of this portion of the spacer to the arch member construction of the truck.

The present invention, like the invention 95 embraced in the co-pending application previously referred to, has a particular object to provide means to relieve the bottom arch member of all bending loads and to relieve the tie members 12 and 13 of a large portion of the load which they ordinarily carry, 100 such as described in the co-pending application. The space available will sometimes prevent the construction shown in the previous application, hence to perform this in the present instance the central portion of 105 the bottom arch member is made straight at 7, and this straight portion terminates at each end in intermediate curved portions 19. From the curved portions, the straight, 110 upwardly inclined, tangential ends 20 ex-

tend to the adjacent ends 21 of the top arch bar to which they are co-actingly secured by means hereinafter to be described.

It has already been explained how the bottom portion of the spacer 11 serves as a load-receiving member. This portion 18 is adapted to transmit such load in turn to the arch members of the truss to and through the bottom arch member 10, and in order to transmit such load to the bottom arch member 10 without inducing bending stresses therein, the load-receiving member 18 is supported near its ends at 8 upon the curved portions 19 of the bottom arch member, and the structure 18 forms a beam, longitudinally of the truck, spanning the distance from one curved portion 19 to the other. Thus the load from the member 18 will be carried by the bottom arch member upon the curved portions 19 only, and such loads will be transmitted to the bottom arch member in directions radial to the curved portions thereof, and no bending stresses will be induced in the bottom portion of the member 10, for the member 18 is not securely riveted or fixed to the bottom arch member along its length but in effect merely rests thereon, the clips 5 and rivets 15 functioning as means for preventing a dis-arrangement of the parts when in use rather than to rigidly secure these parts together. It is in reality preferable that this fastening should allow some slight longitudinal "slip" between the bottom arch member and the member 18.

In order to insure that the curved portions 8 of the member 18 will bear on the curved portions 19 of the member 10, the casting 18 may be cut slightly away over the flat portion 7 as at 33. In order further that the member 18 may be properly seated on the bottom arch bar and that the load will be imparted to the full length of the curved portions, leaving no unsupported portion of the member 10 out of line with the tension loads, the member 18 extends slightly beyond the curves 19, being made with short, straight, tangential extensions 22, which coincide with the tangential portions 20 of the bottom arch bar. Thus the bottom portion of the spacing member forms means for transferring the load to the bottom arch member as direct stresses, and furthermore the tie members 12 and 13 serve now only to take care of the upward reaction due to the angularity of the top arch bar at 23, hence the tie members act in reality between the load-supporting portion 18 and the top arch bar 9 only, the rivets 15 and the clips 5 serving as binders only.

In order to restrain the oil boxes from longitudinal movement and at the same time to take up any load due to the bending of the arch bars over the oil boxes, the tie members 25 are supplied extending from the oil boxes to the truss proper. The oil boxes

thus form in some instances a part of the truss structure. The tie members 25 also serve to restrain the oil boxes when the brakes are applied to the wheels. These tie members 25 are ordinarily attached to the oil boxes by means of the box bolts, but in the truck depicted no box bolts are required, hence the small bolts 26 are supplied for the attachment of the box 3 to the tie bar 25. At 24 I have shown means for attaching this box tie member 25 to the spacing member 11, thus providing means through this spacing member for securing the bottom of the oil boxes to the truss members without weakening the bottom arch member by cutting unnecessary holes in the same, it frequently happening that the fastening such as the rivets 15 and clips 5 are not in a correct location to serve as securing means for the bars 25 also. However, such construction might in some instances be used as indicated at the left in Fig. 1.

It has furthermore been customary in arch bar trucks to bring the top and bottom arch members together over the oil boxes and co-actingly secure these members together by means of the ordinary box bolts. The disadvantage of this form of construction has been pointed out in the co-pending application referred to and the present invention includes improved means for so connecting these various parts. To accomplish this the end of the top arch member 9 is provided with a transversely pierced enlargement 30 and the bottom arch member 10 is made of two parts 27. These terminate in the transversely pierced enlargements 28, which coincide and register with the hole in the enlargement 30.

The portions 27 of the bottom arch member 10 are disposed, transversely of the truck, in spaced relationship with each other, and the intervening space at the ends is occupied by the end of the top arch member. Cast integral with the top of the oil box 3 are ears 34 which are in spaced relation with each other transversely of the truck, and the space between these ears is adapted to admit the assembled ends of the arch members. These ears are likewise pierced with the transverse holes 29 which coincide and register with the holes in the ends of the arch members. When all of these holes are brought into registry and the pin 31 inserted, it will be seen that the ends of the arch members are by this pin co-actingly secured together and at the same time and by the same means the oil box is secured to the side frame. It will be seen further that the pin 31 is in double shear, both for the truss connection and for the oil box connection, these results being attained by the use of the two-part bottom tie member and the two ears on the oil boxes. For transmitting the load of the car verti-

cally to the oil boxes the enlargements 28 and 30 preferably rest on a suitable portion of the oil box. The loads are also centrally equalized by means of this bifurcated arrangement. The use of the two-part bottom arch member further allows the tie member 25 to be passed between the portions 27, so that the attachment 24 to the spacing member 11 may be made at any desired height and in a convenient manner. A further advantage of the two-part bottom arch member will be seen in referring to the construction of the bottom portion 18 of the spacing member 11. It will be recollect 10 that the portion 18 must serve as a beam longitudinally of the truck, and it is furthermore the object to provide such a structure so that the beam action will be entirely independent of the bottom arch member, 15 that is, that the metal of the portion 7 of the bottom arch member shall not be called on to serve as a portion of the beam. In many instances the space is limited for this member 18, and such limited depth makes 20 it difficult to secure a proper or suitable strength. The spaced relationship of the two portions of this bottom arch member allows a portion 35 of the casting 18 to be passed down between the bars 27, whereby 25 greater depth is obtained for the beam 18 without relying on the bottom arch members 30 to assist in the beam action.

The spacing member 11 is shown in the present application as a three-part casting 35 suitably secured together, although it might be made otherwise. Also the customary brake hanger brackets 32 are shown as cast integral with the tie portions of this spacing member.

40 It will be seen that those skilled in the art might make alterations in the embodiment of my invention within the scope of the claims without departing from the spirit thereof.

45 Having thus described my invention, what I claim is:

1. In a car truck, a side frame comprising a top arch member, a bottom arch member in spaced vertical relationship therewith, 50 and a detached central spacing member therebetween, the said spacing member being of U-shape, the vertical legs of the U being secured to and forming tie members between the said arch members, the said bottom arch member embodying a straight, central portion terminating in intermediate curved portions with straight, upwardly inclined, tangential ends extending therefrom to the ends of the said top arch member and 55 being co-actingly secured to said ends of the top arch member, the bottom or transverse member of the said U-shaped spacing member being disposed longitudinally of the truck and being adapted to form a load-re- 60 ceiving seat, the said spacing member be-

ing supported by the said tension member and forming an independent beam spanning from one of said curved portions of the said bottom arch member to the other, and being thereby adapted to transmit the 70 load thereto as direct tension strains only and at the said curved portions only.

2. In a car truck, a side frame comprising a top arch member, a bottom arch member in spaced vertical relationship therewith, 75 and a detached central spacing member therebetween, the said spacing member being of U-shape, the said bottom arch member embodying a straight, central portion terminating in intermediate curved portions 80 with straight, upwardly inclined, tangential ends extending therefrom to the ends of the said top arch member and being co-actingly secured to said ends of the top arch member, the bottom or transverse member of the said 85 U-shaped spacing member being disposed longitudinally of the truck and being adapted to form a load-receiving seat, the said spacing member being supported by the said tension member and forming an independent 90 beam spanning from one of said curved portions of the said bottom arch member to the other and being thereby adapted to transmit the load thereto as direct tension strains only and at the said curved portions 95 only, the vertical legs of the U-shaped spacing member being secured to and forming ties between the said top arch member and the load-receiving portion thereof.

3. In a car truck, a side frame comprising 100 a top arch member, a bottom arch member in spaced vertical relationship therewith, and a detached central spacing member therebetween, the said spacing member being of U-shape, the vertical legs of the U 105 being secured to and forming tie members between the said arch members, the said bottom arch member embodying a straight, central portion terminating in intermediate curved portions with straight, upwardly inclined, tangential ends extending therefrom to the ends of the said top arch member and being co-actingly secured to said ends of the top arch member, the bottom or transverse member of the said U-shaped spacing member 110 being adapted to conform to and bearing upon the curved portions only of the said bottom arch member, and being further adapted to form a load-receiving seat.

4. In a car truck, a side frame comprising 115 a top arch member, a bottom arch member in spaced vertical relationship therewith, and a detached central spacing member therebetween, the said spacing member being of U-shape, the vertical legs of the U being 120 secured to and forming tie members between the said arch members, the said bottom arch member embodying a straight, central portion terminating in intermediate curved portions with straight, upwardly inclined, tan-

- gential ends extending therefrom to the ends of the said top arch member and being co-actingly secured to said ends of the top arch member, the bottom or transverse member 5 of the said U-shaped spacing member being adapted to form a load-receiving seat, the said spacing member being supported by the curved portions of the said bottom arch member and being adapted to transmit the 10 load thereto in directions radial to the said curved portions, the bottom member of the said spacing member forming a beam, longitudinally of the side frame and between the curved portions of the said bottom arch member thereof, independently of the said bottom arch member.
6. In a car truck, a trussed side frame comprising a top compression member, a bottom tension member and a detached central 15 spacing member therebetween, the said spacing member being further adapted to form a load-supporting seat and being secured to the said top and bottom members and being supported upon the said bottom member, the 20 said bottom member embodying a straight central portion terminating in intermediate curved portions with straight, upwardly inclined, tangential ends, the said curved portions being adapted to co-act radially with 25 correspondingly shaped portions of the said spacing member as load-receiving points on the said bottom member, and means for co-actingly securing together the adjacent ends of the said compression and tension members.
7. In a car truck, a trussed side frame comprising a top compression member, a detached central spacing member, and a bottom tension member, the said tension member 30 embodying a straight, central portion terminating in intermediate curved portions with straight, upwardly inclined, tangential ends extending from said curved portions to the adjacent ends of the said top compression member and being co-actingly secured thereto, the said spacing member being of U-shape with the legs thereof forming ties for the said top member and with the bottom thereof adapted to form a load-receiving member, the said spacing member 35 being supported wholly at its ends and upon the said curved portions of the tension member and forming means for imparting the load to the said truss to and through the said tension member in directions radial 40 to the said curved portions.
8. In a car truck, a trussed side frame comprising a top compression member, a detached central spacing member, and a bottom tension member, the said tension member 45 embodying a straight, central portion terminating in intermediate curved portions with straight, upwardly inclined, tangential ends extending from said curved portions to the adjacent ends of the said top compression member and being co-actingly secured thereto, the said spacing member being of U-shape with the legs thereof forming ties for the said top member and with the bottom thereof adapted to form a load-receiving member, the said spacing member 50 being supported wholly at its ends and upon the said curved portions of the tension member and forming means for imparting the load to the said truss to and through the said tension member in directions radial 55 to the said curved portions.
9. In a car truck, a trussed side frame comprising a top compression member, a detached central spacing member, and a bottom tension member, the said tension member 60 embodying a straight, central portion terminating in intermediate curved portions with straight, upwardly inclined, tangential ends extending from said curved portions to the adjacent ends of the said top compression member and being co-actingly secured thereto, the said spacing member being of U-shape with the legs thereof forming ties for the said top member and with the bottom thereof adapted to form a load-receiving member, the said spacing member 65 being supported wholly at its ends and upon the said curved portions of the tension member and forming means for imparting the load to the said truss to and through the said tension member in directions radial 70 to the said curved portions.
10. In a car truck, a side frame comprising a top arch member, a bottom arch member in spaced vertical relationship therewith, the bottom arch member embodying a straight, central portion terminating in intermediate curved portions with straight, 75 upwardly inclined, tangential ends extending from said curved portions to the adjacent ends of the said top arch member, and being co-actingly secured thereto, a load-supporting beam portion extending longitudinally of the said bottom arch member 80 from one of the said intermediate curved portions thereof to the other and being supported on said curved portions, and tie members secured to and forming tension mem- 85
11. In a car truck, a side frame comprising a top arch member, a bottom arch member in spaced vertical relationship therewith, the bottom arch member embodying a straight, central portion terminating in intermediate curved portions with straight, upwardly inclined, tangential ends extending from said curved portions to the adjacent ends of the said top arch member, and being co-actingly secured thereto, a load-supporting beam portion extending longitudinally of the said bottom arch member 90 from one of the said intermediate curved portions thereof to the other and being supported on said curved portions, and tie members secured to and forming tension mem- 95
12. In a car truck, a side frame comprising a top arch member, a bottom arch member in spaced vertical relationship therewith, the bottom arch member embodying a straight, central portion terminating in intermediate curved portions with straight, upwardly inclined, tangential ends extending from said curved portions to the adjacent ends of the said top arch member, and being co-actingly secured thereto, a load-supporting beam portion extending longitudinally of the said bottom arch member 100 from one of the said intermediate curved portions thereof to the other and being supported on said curved portions, and tie members secured to and forming tension mem- 105
13. In a car truck, a side frame comprising a top arch member, a bottom arch member in spaced vertical relationship therewith, the bottom arch member embodying a straight, central portion terminating in intermediate curved portions with straight, upwardly inclined, tangential ends extending from said curved portions to the adjacent ends of the said top arch member, and being co-actingly secured thereto, a load-supporting beam portion extending longitudinally of the said bottom arch member 110 from one of the said intermediate curved portions thereof to the other and being supported on said curved portions, and tie members secured to and forming tension mem- 115
14. In a car truck, a side frame comprising a top arch member, a bottom arch member in spaced vertical relationship therewith, the bottom arch member embodying a straight, central portion terminating in intermediate curved portions with straight, upwardly inclined, tangential ends extending from said curved portions to the adjacent ends of the said top arch member, and being co-actingly secured thereto, a load-supporting beam portion extending longitudinally of the said bottom arch member 120 from one of the said intermediate curved portions thereof to the other and being supported on said curved portions, and tie members secured to and forming tension mem- 125
15. In a car truck, a side frame comprising a top arch member, a bottom arch member in spaced vertical relationship therewith, the bottom arch member embodying a straight, central portion terminating in intermediate curved portions with straight, upwardly inclined, tangential ends extending from said curved portions to the adjacent ends of the said top arch member, and being co-actingly secured thereto, a load-supporting beam portion extending longitudinally of the said bottom arch member 130 from one of the said intermediate curved portions thereof to the other and being supported on said curved portions, and tie members secured to and forming tension mem-

bers between the said beam portion and the said top arch member.

11. In a car truck, a plurality of axles and oil boxes, a side frame supported at its ends upon the oil boxes of adjacent axles, said side frame comprising top and bottom arch members in spaced vertical relationship with each other at their central portions and having spacing means therebetween, 10 tween and converging at their ends to points over the said oil boxes, the said bottom arch member being formed of two parallel and laterally-spaced members at the ends, the ends of the said top arch member being disposed between the adjacent ends of the said bottom arch member, spaced lugs on said oil boxes, holes transversely of the truck through the said spaced lugs of the oil boxes and the ends of the top and bottom 15 arch members, said holes being in registry over the said oil boxes, and pins adapted to co-actingly connect the said arch members and the said oil boxes.
12. In a car truck, the combination with 20 a plurality of wheels, axles and oil boxes of
11. In a car truck, a plurality of axles and oil boxes, a side frame supported at its ends upon the oil boxes of adjacent axles, the said side frame comprising a top compression and a bottom tension member, the said compression and tension members being co-actingly secured together at their ends and being disposed in spaced vertical relationship with each other at their central portions and with spacing means therebetween, the said bottom tension member being composed of two portions in spaced transverse relationship with each other, means for securing the ends of the said compression and tension members to the oil boxes, and a tie strap secured at its outer end to an oil box 30 and at its inner end to the said spacing means, the said tie strap being disposed between the said spaced portions of the said tension member. 35
12. In a car truck, the combination with a plurality of wheels, axles and oil boxes of
13. In a car truck, a side frame supported at its ends upon the oil boxes of adjacent axles, the said side frame comprising a top compression and a bottom tension member, the said compression and tension members being co-actingly secured together at their ends and being disposed in spaced vertical relationship with each other at their central portions and with spacing means therebetween, the said bottom tension member being composed of two portions in spaced transverse relationship with each other, means for securing the ends of the said compression and tension members to the oil boxes, and a tie strap secured at its outer end to an oil box 40 and at its inner end to the said spacing means, the said tie strap being disposed between the said spaced portions of the said tension member. 45

In testimony whereof, I affix my signature in presence of two witnesses.

JOHN A. PILCHER.
